ELASTIC FABRIC

Neil A. Crimmins, Stoughton, Mass., assignor,
by mesne assignments, to United States Rubber Products, Inc., New York, N. Y., a corporation of Delaware

Application April 11, 1932, Serial No. 604,586

6 Claims. (Cl. 66—190)

This invention relates to elastic fabrics of the kind used in the manufacture of corsets, brassières, belts, bathing suits, stockings, surgical and other articles in which elastic fabrics enter into the construction in one way or another.

The principal object of the invention is to provide an improved light-weight elastic fabric having a controlled amount of stretch in two different directions.

Another object of the invention is to provide a thin, light-weight, strong and durable knitted elastic fabric of decidedly porous texture, having a restricted short, snappy stretch and quick contraction in the direction of the knitted loops, and a long easy stretch in the direction of the courses.

Another object of the invention is to provide an elastic fabric of the type referred to, in which the interlaced elastic and inelastic threads cooperate to establish a firm anchorage for sewing machine stitches when sections of the fabric are sewed together or to other sections of cloth as in the manufacture of corsets and the like.

Most of the elastic fabrics heretofore used in the manufacture of corsets and other extensible garments have possessed only a one-way stretch. This has been obtained by knitting, weaving or braiding cotton, silk, rayon or other inextensible threads in the customary manner, and inserting covered rubber threads between the rows of knitted loops, or between the warp or braiding threads, depending upon the type of fabric employed. This gives the required longitudinal extension and contraction in the fabric, or circumferential extension and contraction in the finished garment, but makes no provision for stretch in a transverse direction.

When elastic fabrics of this type are used in corsets and other garments the circumferential extension and contraction are usually satisfactory, confining the diaphragm and abdomen in accordance with the dictates of fashion, but the results are more or less unsatisfactory to the wearer because bodily movements in a forward or sidewise manner cause the garment to get out of position or "ride up" on the figure with considerable discomfort to the wearer and necessarily requiring constant readjustment. Modern scientific development shows that much better results can be obtained by using an elastic fabric having the desired degrees of extension and contraction in both directions, that is, vertically and horizontally as used in the garment.

Some attempts have been made to construct an elastic fabric having a two-way stretch, but these attempts have usually resulted in unattract-

tive, loose sleazy structures without the necessary controlled stretch or constricting qualities required in modern garments. Other attempts have resulted in tightly knitted open structures similar to what is known as the grenadine stitch on warp knit fabrics, but these fabrics never had the proper controlled stretch and their texture has been too harsh and irritating to permit them to be worn next to the body.

My improved elastic fabric may be constructed in various ways, but it preferably comprises a knitted structure having a restricted short, snappy stretch and quick contraction in the direction of the knitted loops, and a long easy stretch in the direction of the courses. When the fabric is used in a corset or similar garment, the short snappy stretch and quick contraction in the direction of the loop supplies the restriction and regulation of tension required in a circumferential direction, while the long easy stretch in the direction of the courses supplies the vertical extension and contraction required to accommodate the garment to the natural bending movements of the body. When such a garment is once adjusted it will always remain in place, all movements of the body being adequately compensated by the controlled two-way stretch, with a decided increase in comfort and convenience to the wearer.

My elastic fabric is also considerably lighter, thinner and more porous than previous elastic fabrics which have usually employed bulky covered rubber threads in order to give the desired stretch. Where previous fabrics have used heavy rubber threads of considerable tensile strength, laid between the loops of alternate courses, I use a very fine rubber thread having very little tensile strength in itself, but looped and interwound so closely and so many times that it makes a strong fabric which is much lighter and decidedly more comfortable to wear than previous fabrics employed in the manufacture of garments.

In the preferred form of the invention I obtain these and other improved results in a knitted fabric employing a novel construction of knitted loops, having a relatively large number of inelastic courses composed of fine silk, cotton yarn or the like, and a relatively small number of intermediate courses composed of fine covered elastic threads interspersed throughout the fabric and interlooped with said inelastic threads, and preferably having additional covered elastic threads laid in unlooped fashion between the loops of certain of the inelastic courses. The principal factor of elastic strength resides in the

25

30

35

40

45

50

55

unique loop formation of the covered rubber threads, which also gives the fabric a greater holding surface for sewing machine stitches. Hence, in addition to its other advantages, my 5 fabric minimizes the difficulties previously encountered in the manufacture of corsets and other garments due to the slippage of the inserted elastic thread through the rows of sewing machine stitches when sections of the elastic fabric are sewed together or to other sections of cloth.

These and other features and advantages of the invention will be described in connection with the accompanying drawings, in which:

15 Fig. 1 is a plan view, on a slightly enlarged scale, showing one form of knitted elastic fabric constructed according to my invention;

20 Fig. 2 is a similar view on a greatly enlarged scale and with the proportions exaggerated some- what to show the unique loop formation and the relative positions of the elastic and inelastic threads;

25 Fig. 3 is an enlarged view showing the fabric stretched horizontally, or in the direction of the loops;

Fig. 4 is a similar view showing the fabric stretched in a vertical direction, or in the direction of the courses;

30 Fig. 5 is an enlarged view showing one form of covered elastic thread which may be employed in the construction of the fabric;

35 Fig. 6 is a side view of a torso wearing a corset containing an elastic fabric constructed according to the invention, illustrating the two-way stretch when in a standing position; and

Fig. 7 is a similar view illustrating the adjustment of the fabric when the wearer assumes a bending or sitting position.

In the fabric shown in Figs. 1 and 2, the strand 40 1 is a fine covered elastic thread of any suitable construction, such as that shown Fig. 5 which will be described later. This course is knitted on two sets of needles, either on a machine well known in the art as a circular dial-to-cylinder 45 machine, in which the cylinder and dial may revolve and the cam ring remain stationary, or the cam ring revolve and the cylinder and dial remain stationary; or on a flat or straight bed machine in which flat beds accommodating and actuating 50 the needles are in opposite relation to each other. The needles in the dial and cylinder in the opposing flat beds pull the loops in opposite directions.

The course 2 may consist of fine rayon or other suitable textile fibres knitted on both sets 55 of needles. A covered elastic thread 3, which may be similar in construction to the thread 1, is laid between the loops of the course 2. The course 4 may be a fine rayon and cotton thread, with the rayon plated on the cotton so as to 60 present a silky surface, although any other suitable textile fibre may be employed.

In each course 4 the thread is knitted in alternate wales and floated past the intervening wales of the adjacent courses as indicated at 6 in Fig. 2. 65 The course 4 is knitted on only one set of needles, the other set of needles remaining inactive but retaining their loops from the preceding course 5. The course 5 may consist of rayon, knitted on both sets of needles, pulling their loops in opposite direction. The foregoing arrangement of 70 courses is then repeated as best shown in Fig. 2.

The elastic threads 1 and 3 may be of the type disclosed in a copending application of N. A. Crimmins and W. F. Alden, Serial No. 513,492, filed February 5, 1931, Patent No. 1,853,551, issued

April 12, 1932, one form of which is illustrated in Fig. 5. This thread consists of one or more rubber core threads or strands 7 on which are wrapped a plurality of superimposed spirally wound textile cover threads 8, 9, 10 and 11. 5

The innermost cover 8, consisting of two ends of suitable textile fibres such as cotton, is wound upon the rubber core preferably with a short pitched close spiral so that it completely encloses the rubber core when in the normal contracted 10 condition shown in the drawings.

The second cover 9 is generally similar to the first cover, but is preferably composed of three ends of textile fibres wound in the opposite direction over the first cover, also in a short pitched 15 close spiral. The covers 8 and 9 together substantially cover and conceal the rubber core even when it is stretched to the limit of its elasticity.

The third cover 10 is preferably composed of one end of fine, hard twisted cotton which is 20 wound tightly over the inner covers in a long pitched open spiral running in the opposite direction to the cover 9. The fourth cover 11 is also composed of one end of hard twisted cotton which is wound in an opposite direction to the cover 10, 25 also in a long pitched open spiral.

The covers 8 and 9 serve to protect and strengthen the rubber core, and also cooperate in controlling the stretch thereof. Covers 10 and 30 11, with their long pitched open spirals, cooperate in compressing the first two covers, causing the resulting extensible encasement to grip the rubber core and causing the cover 9 to protrude or bulge out between the open spirals, raising countless small ridges or corrugations continuously around the outer surface of the thread.

The several covers forming the encasement about the rubber core 7 will tighten and reach the breaking point at substantially the same time, well within the elastic limit of the rubber core, 40 limiting the stretch of the rubber and insuring that the breaking points of the core and all the covers are reached at approximately the same point. The roughened or bulging gripping surfaces of the covered elastic threads cooperate 45 with the knitted loops of the fabric to retard slippage, and also provide a substantial holding surface for sewing machine stitches when sections of the elastic fabric are stitched together or to other sections of cloth. 50

Fig. 3 shows the elastic fabric stretched horizontally, or in the direction of the knitted loops, while Fig. 4 shows the fabric stretched in a vertical direction, or in the direction of the courses. The relatively large number of inelastic courses 55 are closely knitted in loop formation, permitting the fabric to extend more in the direction of the courses than in the direction of the loops. Hence the relatively small number of interposed elastic courses 1, closely interlooped with the adjacent inelastic courses, give the fabric a short snappy stretch and quick contraction in the direction of the loops as indicated in Fig. 3, while the elastic courses 1 and inlaid elastic threads 3 give 60 the fabric a long easy stretch in the direction of 65 the courses (lengthwise of the threads 1 and 3) as shown in Fig. 4.

The advantage of this unique two-way stretch is illustrated in Figs. 6 and 7 which show a corset 70 12 of any suitable type, having side elastic inserts 13 constructed in accordance with my invention. The knitted loops or wales extend horizontally or circumferentially in the garment, while the courses run in a vertical direction, as previously described in connection with Figs. 2 to 4. The 75

short snappy stretch and quick contraction in the direction of the knitted loops supply the restriction and regulation required in a circumferential direction in any position the wearer may assume. The long easy vertical stretch, in the direction of the courses, enables the garment to adjust itself easily when the wearer assumes a sitting position, or bends over in any direction. Consequently the garment has no tendency to get out of position or ride up on the figure as heretofore.

It will also be seen that the above construction and incorporation of knitted courses of fine rubber thread and inserts of unlooped fine rubber thread make it possible to obtain a greater degree of porosity than heretofore, giving better ventilation and absorbing perspiration more readily, in a thin light-weight fabric of the requisite tensile strength and with a regulated restricted degree of extension and contraction.

For the purposes of illustration I have shown and described one particular fabric embodying my invention, but it will be evident that various changes may be made in details of construction without departing from the scope and spirit of the invention as defined in the appended claims.

The invention claimed is:

1. An elastic fabric having a relatively large number of courses composed of inelastic threads knitted in loop formation, a relatively small number of courses composed of elastic threads interspersed throughout said fabric and interlooped with the inelastic threads of adjacent courses, and elastic threads laid between the loops of inelastic threads of certain courses, said elastic threads each having a rubber core, an inner cover and an outer cover wound around the inner cover in a long pitched spiral compressing the inner cover and causing it to bulge out between the convolutions of the outer cover.

2. An elastic fabric having a relatively large number of courses composed of inelastic threads closely knitted in loop formation, permitting the fabric to extend more in the direction of the courses than in the direction of the loops, a relatively small number of courses composed of elastic threads interspersed throughout said fabric and interlooped with the inelastic threads, and elastic threads laid between the loops of certain of said inelastic threads, giving the fabric a short snappy stretch and quick contraction in the direction of the loops and a long easy stretch in the direction of the courses.

3. An elastic fabric having a relatively large number of courses composed of inelastic threads knitted in loop formation, the threads being knitted in alternate wales and floated past the intervening wales in certain of said courses, a relatively small number of courses composed of elastic threads interspersed throughout said fabric and interlooped with the inelastic threads, and

elastic threads laid between the loops of certain of said inelastic threads, giving the fabric a short snappy stretch and quick contraction in the direction of the loops and a long easy stretch in the direction of the courses.

5

4. A light, porous elastic fabric having a relatively large number of courses composed of fine inelastic threads closely knitted in loop formation, permitting the fabric to extend more in the direction of the courses than in the direction of the loops, a relatively small number of spaced courses composed of fine elastic threads interspersed throughout said fabric and each interlooped with the inelastic threads of adjacent courses, and a plurality of fine elastic threads laid between the loops of certain of said inelastic courses, giving the fabric a short snappy stretch and quick contraction in the direction of the loops and a long easy stretch in the direction of the courses.

20

5. A light, porous elastic fabric having a relatively large number of courses composed of fine inelastic threads closely knitted in loop formation with alternate loops of certain courses dropped and floated across the wales of adjacent courses, permitting the fabric to extend more in the direction of the courses than in the direction of the loops, a relatively small number of spaced courses composed of fine elastic threads interspersed throughout said fabric and each interlooped with the inelastic threads of adjacent courses, and a plurality of fine elastic threads laid between the loops of certain of said inelastic courses, giving the fabric a short snappy stretch and quick contraction in the direction of the loops and a long easy stretch in the direction of the courses.

30

6. A light, porous elastic fabric having a relatively large number of courses composed of fine inelastic threads closely knitted in loop formation, permitting the fabric to extend more in the direction of the courses than in the direction of the loops, a relatively small number of spaced courses composed of fine elastic threads interspersed throughout said fabric and each interlooped with the inelastic threads of adjacent courses, and a plurality of fine elastic threads laid between the loops of certain of said inelastic courses, giving the fabric a short snappy stretch and quick contraction in the direction of the loops and a long easy stretch in the direction of the courses, said elastic threads each having a rubber core, an inner cover wound around the core in a short pitched spiral and an outer cover wound around the inner cover in a long pitched spiral compressing the inner cover and causing it to bulge out between the convolutions of the outer cover.
